REMOTE CONTROL FOR RADIO RECEIVERS

Donald C. Fierce, St. Albans, N. Y.

Application August 6, 1938, Serial No. 223,497

9 Claims. (Cl. 250—20)

This invention relates to controlling devices for radio receiving sets and particularly to an improved compact electrically actuated remote control, an object being to provide a construction which will accurately control the tuning of a radio receiving set from one or more remote points as well as at the receiver.

Another object of the invention is to provide a remote control device which may be easily actuated by the operator and which will accurately tune to the various selected stations.

A further object of the invention is to provide a remote control device for radio receiving sets which is adapted to have the principal parts mounted on the receiver and the other parts extending to any desired distance so as to be controlled and manipulated from a distance with the parts adapted to tune or move the condenser in either direction for selecting a desired station.

20 In the accompanying drawings—

Fig. 1 is a front view of the principal part of the device embodying the invention, the cover and dial pointer being removed;

Fig. 2 is an enlarged view of the structure shown in Fig. 1, a tuning condenser being shown in dot-and-dash lines;

Fig. 3 is a plan view of the structure shown in Fig. 2, part of the casing being shown in section;

Fig. 4 is a side elevation showing the opposite side of the device to that illustrated in Fig. 2, the cover and certain parts being eliminated;

Fig. 5 is a perspective view of a pair of armatures with a non-magnetic connecting member;

Fig. 6 is a perspective view on a reduced scale of the structure shown in Fig. 5 associated with a magnet embodying certain features of the invention;

Fig. 7 is a sectional view through Fig. 2 approximately on the line 7—7, showing a detail step-by-step switch, cam, and cam holding means;

Fig. 8 is a sectional view through Fig. 7 approximately on the line 8—8;

Fig. 9 is a detail view of the step-by-step switch shown in Fig. 7;

Fig. 10 is a detail view partly in section and partly in elevation showing a cam holding mechanism embodying certain features of the invention;

Fig. 11 is a view showing in elevation a brush embodying certain features of the invention;

Fig. 12 is an elevation of the tuning wheel, the connection to the tuning condenser, and the on-and-off switch structure;

Fig. 13 is a top plan view with certain connec-

tions in section and illustrating a hand control switch;

Fig. 14 is a side view of the structure shown in Fig. 13;

Fig. 15 is a view of the structure shown in Fig. 14 on the opposite side and illustrating the three control buttons;

Fig. 16 is a sectional view through Fig. 15 approximately on the line 16—16;

Fig. 17 is a diagram of the circuit;

Fig. 18 is a fragmentary perspective view showing the swinging arm and an armature and associated parts illustrated in Fig. 1;

Fig. 19 is a detail perspective view of a ratchet wheel and brushes illustrated in Figs. 1 and 2;

Fig. 20 is an end view of the ratchet wheel shown in Fig. 19 and illustrating the various springs and spring contacts shown at the right in Fig. 18 and also shown at the center in Fig. 2.

Referring to the accompanying drawings by numerals, 1 indicates a frame which may be of any desired material, as for instance a non-magnetic metal such as aluminum or zinc alloy. This frame is secured in place on a receiver in any suitable way, as for instance by a number of screws 2. Also the structure shown in Figs. 1 and 2 is preferably mounted on the receiver at the usual place occupied by the dial. This makes it convenient for connection with the usual tuning condenser 3 forming part of the receiving set or receiver. The condenser 3 may be tuned electrically or by hand independently of the volume control 4, which also may be tuned by hand at the receiver or electrically at a remote point.

Preferably when it is desired to set a station on the remote control the shaft 5, shown in Figs. 1 to 7 and 10 is rotated to a position where the finger 6 enters a depression 7 in the enlarged portion 8 of shaft 5 and then the cam shaft 18 and the tuner condenser 3 are manually rotated to tune in the desired station. Preferably the shaft

5 (Fig. 10) is provided with a hand-operated knob 9 and a pointer 10 adapted to move over a scale on a casing 11. It will be noted from Fig. 7 that the finger 6 moves on a pivotal pin 12 and is urged by a spring 13. When the finger 6 moves into the notch or depression 7 it will swing the arm 14 so that the notch 15 formed therein will move over the stop 16 preferably pressed out from the cam 17.

As indicated in Fig. 10, the various depressions or notches 7 in the enlarged portion 8 are arranged spirally in such a manner that only one of the fingers 6 can be depressed or moved into a notch 7 at a given point. It will therefore be

10

15

35

40

45

50

55

seen that the arm 14 serves to hold the cam 17 stationary while the cam shaft 18 and the tuning condenser 3 are manually rotated to tune in the station.

The cam shaft 18, as shown in Figs. 1, 7 and 8 and the upper part of Fig. 17, carries a number of cams 17. Illustrated particularly in Fig. 8, there is provided a cam for each wave length that is to be tuned to electrically. In the accompanying drawings there are shown ten in the circuit (Fig. 17) and the detail arrangement of the parts is illustrated in Fig. 8. Between the respective cams, which are rotatably mounted on the various sleeves 18' and 18'', there are substantially flat spider formations 77, which are rigidly connected by keys, solder, or other means to shaft 18 between the sleeves or rings 18'' and the sleeve 18' so as always to rotate with shaft 18. The various cams 17, however, are individually freely rotatable on the rings 18'', though ordinarily they do not do so because of the friction of the spiders 77 which are tensioned against the flat surface of the respective cams. It will be noted from Fig. 7 that each cam is provided with a small arc-shaped portion 78 and a large arc-shaped portion 79 with offsets or cam sections 80 and 81 connecting these arc-shaped portions. As shown particularly in Figs. 1 and 2, shaft 42 has an end journaled in the end of stub shaft 42' and connected to said stub shaft by a spiral spring 66. The stub shaft 42' is secured to shaft 42 which is secured to gear wheel 67, which gear wheel is in continuous mesh with gear wheel 68 and gear wheel 69, through a suitable shaft and miter gear structure 69, is connected to shaft 70 to which a gear wheel 71 is rigidly secured. By reason of this construction, whenever motor 21 starts to function it will move the shaft 22 longitudinally to the left against the action of spring 22' and, consequently, it will move the pinion 72 into mesh with the gear wheel 71. It is to be noted that motor 21 is a well-known structure of the kind that is reversible so as to be readily operable in either direction. It will be seen, therefore, that when the pinion 72 secured to shaft 22 is in mesh with gear wheel 71, power will be transmitted through the miter gear 69 to pinion 68 and then to gear wheel 67. From gear wheel 67 motion will be transmitted from the shaft 22 for rotating the pinion 46, as shown in Fig. 2. From this arrangement it will be readily seen that the action of magnet 27 and armature 29 will shift pinion 46 by the rocking of the bar 30 over into engagement with the gear wheel 47 and then the rotation of the motor 21 will give the parts the required rotary movement to secure the desired tuning action. When the armature 29 (Fig. 18) is attracted by magnet 27, pinion 46 will swing over into engagement with gear wheel 47 and when the armature 29 is released the pinion 46 will automatically swing back into mesh with the gear wheel 48.

Referring again to Figs. 1, 2 and 18, it will be seen that the rotatable shaft 42 extends through a slot 43 in block 36 and rotatably extends through a spring 44, which spring is secured at 45 to arm 33. This allows a slight independent movement of block 36 and arm 33 to the left when the pinion 46 rigidly secured to shaft 42 is moved over against either of the bevel gears 47 and 48. The spring 44 permits a yielding action in case the teeth of the pinion and gear do not mesh when they are brought into contact. When the parts are in the position shown in Fig. 2, the pinion 46 is in mesh with the gear wheel

48, which gear wheel is loosely mounted on a tubular stub shaft 1' which may be an integral extension of frame 1. A small pinion 50 is also loosely mounted on the tubular stub shaft 1', but rigidly secured to gear wheel 48. The pinion 50 is continually in mesh with a large gear wheel 51 which is rigidly secured to a shaft 52. The arm 23 is also rigidly secured to shaft 52 so that when gear wheel 51 rotates in either direction arm 23 will be swung accordingly. A pulley 53 is likewise secured to shaft 52 and coacts with a pulley 54 rigidly secured to a shaft 55. The shaft 55 is connected with the volume control 4 so that when it is rotated the volume will be increased or decreased according to the direction of rotation. The belt portions 56 and 57 of a divided belt are secured to the respective pulleys 53 and 54 and are wound in opposite directions thereon so that when one belt is being wound on a given pulley the opposite belt is being unwound therefrom. This arrangement permits a ready and convenient way of moving the volume control 4, which may be of any desired kind and also by reason of the pulley sections may be arranged at any convenient point on the receiver. This arrangement permits the volume control 4 to be rotated more than 180° and, if desired, could be arranged to rotate the control 360°.

The shaft 55 may be provided with a knob and operated manually if desired. The shaft 49 also may be provided with a knob operated manually if desired. The bevel gear 47 is rigidly secured to shaft 49 so that when the arm 33 is swung to the left, as shown in Fig. 2, pinion 46 moves out of mesh with gear wheel 47. When pinion 46 and gear 47 are in mesh and pinion 46 is rotated, shaft 49 will be rotated to produce the desired tuning.

It will be observed (Fig. 2) that a friction pulley 58 is secured to shaft 49 and frictionally engages a comparatively large disk or wheel 59 which is secured to shaft 18 carrying the pointer 61 on the face of the device. A substantially S-shaped resilient flexible coupling 62 (Fig. 12) is secured at 63 and 64 to the disk 59 and also to the tuning shaft 65 of the condenser 3. By rotating the shaft 49 the required distance the desired tuning may be secured. This may be accomplished electrically or manually.

After the arm 14 has been swung to the right, as shown in Fig. 7, to engagement with the stop or abutment 16, the cam 17 connected therewith will be held stationary while the cam shaft 18 and the tuning condenser 3 will be manually rotated to tune in the desired station. If the stop or abutment 16 is not in position to engage the notch 15 in the arm 14, it will be necessary to rotate the tuning element until the parts are in registry. This may be done electrically, since the point where the cam stops the rotation of the tuning condenser 3 when it is used to bring in a station, is that in which the abutment 16 is directly opposite the notch 15 and the brushes 73 and 74 lose contact with the cam 17. At this point the brush 73 rests against the insulation 75 and the brush 74 rests against the insulation 76. The shaft 5 is then rotated manually back to a neutral position, as shown in Fig. 7, when the control has been properly set to control a station.

The ratchet wheel 35, as shown in Figs. 7, 19 and 20, is connected directly to the brushes 97 and 98 which move over the contact bars 110 and 111 and at different times move into engagement with the respective contacts 73 and 74. When the spring and pawl 34, as shown in Figs. 2 and 75

18, is vibrated to move the ratchet wheel step by step, the respective pins 91 and 92 are moved around and eventually into engagement with the depressed parts or sockets 41' and 96'' whereby the contact 96' is separated from the contact spring 93 and the contact spring 41 is separated from the contact spring 39 and brought into engagement with the contact spring 38.

From Figs. 18 and 20, it will also be readily observed that when the bar 30 is rocked by the magnet 27 attracting the armature 29, the rod of insulation 31 will be pulled and the spring arm 40 will be moved so as to separate its engagement with spring contacts 93 and also to move the contact arm 39 into engagement with arm 41 and arm 38 out of engagement with arm 41.

Referring more particularly to Fig. 17 of the drawings, it will readily be seen that several remote speakers could be operated by a push button structure, as shown in Figs. 15 and 16, or other suitable means. The push button structure shown in elevation and in section in Figs. 15 and 16 presents a very convenient and desirable construction for portable use as it shows a unit small enough to be held in the palm of the hand of the operator and be readily operated by the thumb of the same hand.

If dynamic speakers are used at remote points direct current for energizing the field magnets 30 may be taken from a common source or from a rectifier which may be switched on and off with the receiver. The speakers are preferably equipped with what may be termed "lock-in contact springs," as shown in Fig. 17, in which member 82 is a small armature before the face of the pull piece of the speaker 83. This armature is attached through the insulating rod 84 to a spring 85. When the speaker field 26 is energized the contacts 86 and 87 close. When this occurs contacts 86 and 88 break while contacts 89, 90 and 88 close.

By momentarily pressing the button 19 of the push button control unit, shown in Figs. 15 and 16, a circuit is closed through the speaker field 26 which establishes sufficient flux to attract the armature 82 and lock in the associated contacts above described. When the receiver is switched off all of these contacts are released. It should be understood, therefore, that the speaker may 50 be cut-in from any of the remote stations associated with it and that other speakers may be cut-in at remote stations associated with them, and that all speakers are cleared of the system by switching the receiver off from any point.

55 When the button 19 (Fig. 17) has been pressed the motor 21 will be started and certain actions will take place. When the button 19 is released the magnet 27 will be deenergized but the remote speaker field 26 will be locked in through the contacts 86 and 87. The armature 29 and the pawl 34 rotate the ratchet wheel 35 (Figs. 2 and 20) one tooth so that the projecting pins 91 and 92 act on the contact springs 41 and 96 for disengaging them. The pins 91 and 92 may be of insulating material or of metal and mounted on insulating material. The armature 28 will also be released and if no station is to be selected at this time the alternating current to the motor 21 through the contact spring 41 and contacts 39, 94 and 95 will be closed. However, when the motor 21 attempts to start it will trip the spring-actuated arm 96 which will move contact 96' (Figs. 2 and 17) into contact with the spring 93 and thus cause the magnet 27 to vibrate the armature 29. This action is continued so as to pro-

duce a making and breaking of contact springs or members 40 and 93. This will cause the pawl 34 (Fig. 2) to function and move the ratchet wheel 35 and brushes 97 and 98 until the parts reach the normal position shown in Fig. 2, whereupon the pins 91 and 92 will separate the contact springs 41 and 96. From Fig. 7 it will be seen that the brushes 97 and 98 are carried by the hub of ratchet wheel 35 so that the brushes will move with the ratchet wheel. The armature 28 is also held operated and the contacts 106 and 107 are held separated during this vibration by a weak current passing through the resistance 99 (Fig. 17) and the condenser 100 and also resistance 101 to prevent radiation of the make-and-break current over the external control wires. In case it is desired to select a station immediately after the receiver is switched on, the button 19 will be vibrated in order to give a series of impulses corresponding to the desired station. From Fig. 17 it will be seen that when the button 19 is depressed to close the contact 20, the contact 102 also closes, but when the button 103 is depressed to close contact 102, contact 20 does not close.

It will also be observed that a weak current is kept flowing through the magnet 27 and resistances 104 and 105 to hold the armature 28 operated during the series of impulses which are being made with the button 19. Upon the full release of button 19, armature 28 will be deprived of current and establish a direct current circuit through the magnet 27, contacts 106 and 107, magnet 113, magnet 108, or wire 109, depending upon which of the brushes 73 or 74 is in contact with the cam 17, arcs 110 and 111 of the step-by-step switch brush 97 or 98, brush 73 or 74, cam 17, and shaft 18 to the ground. This operates structure 114 and holds the armature 28 in a non-operated position by the action of magnet 113 on armature 114. The motor 21 starts and rotates the cam assembly and tuning condenser to bring in the desired station, the direction of rotation being controlled by the contacts 115, 94 and 95, the latter two being under control of the armatures 28 and 112. When the circuit is broken at the same brushes 97 and 98, the armature 28 immediately operates and the step-by-step switch is returned to normal as heretofore described.

Referring more particularly to Figs. 14 and 15, it will be seen that the push buttons 19, 103 and 116 are mounted for convenient use when the assembly is held in the hand. It will also be noted that the contact 20 is very short while the contacts 119 and 102 are comparatively long.

From Figs. 15, 16 and 17 it will be seen that there has been provided three metal springs, namely, springs 19', 120 and 116', all electrically connected together and preferably made from a single piece. Spring 120 is tensioned to move into contact with pin 102. Spring 19' is tensioned to move in an opposite direction to spring 120 and is provided with an extension 121 projecting beneath spring 120 for normally holding the same out of contact with pin 102. When the button 19 is depressed spring 120 will be released so that it will immediately contact pin 102. When the button 116 is depressed only the contact 119 will be engaged. In tracing the various circuits it will be observed that when the button 19 is depressed alternating current will be drawn from any suitable supply through the wires 123 and 124.

In the lower left-hand corner of Fig. 17 a diagram indicating a telephone dial is presented which illustrates how a telephone dial may be used instead of the switch buttons 19, 103 and 75

116. When using the telephone dial, contacts 151 and 152 close when the dial is moved from a normal or inoperative position and remain closed until it returns to that position. The contacts 5 149 and 150 also remain closed while the dial is rotated manually but make and break as the dial returns to normal, while the push buttons 20' and 119' serve to adjust the volume. It will be understood that as the dial is swung off normal to select a station, the receiver is switched to the "on" position if at the "off" position. As the dial returns it interrupts the direct current established through the magnet 27 so as to serve the same purpose as the push buttons 103 and 19. The 10 resistances 154 and 99 have a value equal to the combined resistance of resistance coils 104 and 105 or coils 104' and 105'.

The various circuits of the various parts are shown in diagram in Fig. 17 to which reference is 20 now made. When button 19 is depressed alternating current flows through a circuit including the winding 26. Assuming that the switch 24 is open or in the "off" position and starting with contact 20, after button 19 has been depressed, 25 alternating current will flow through wire 125 to contact 88, contact member 86, wire 126, winding 26, wire 127, wire 128, wire 129, contact post 130, switch blade 131, contact post 132, wire 123 to alternating current generator, and from the 30 generator (not shown) to wire 124, through resistance 133, wire 134 to winding section 135 of motor 21, wire 136, wire 137, post 138, switch blade 139, wire 140, wire 141 to contact 20. Current flowing in this circuit will cause motor 21 35 to function thereby throwing the switch 24 to the "on" position. This will cut out the supply of alternating current and turn on the direct current from the rectifier 25' or from an outside source if switch 142 is closed or at the "on" position. If this switch is in the "off" position direct current will be supplied by the rectifier 25'. While this is taking place the pawl 34 and associated parts have functioned for causing contacts 93 and 96 (Fig. 20) to close and contacts 38 and 41 to open and contacts 39 and 41 to close. Direct current will then flow from the rectifier 25' to the ground and then to contact 96, through contact 96', contact spring 93, contact spring 40, wire 143, wire 144, windings of magnet 27, wire 155, wire 146, and wire 147 back to the rectifier 25'. Direct current flowing in this path will energize magnet 27 and cause this magnet to attract armatures 28 and 29. The attraction of armature 29 will cause arm 33 to swing to the left, as shown in Fig. 2, and as heretofore set forth. The attraction of armature 28 will cause the rod 148 to swing contact 107 away from contact 106 and at the same time swing contact 95 away from contact 94 and move contact 95 into engagement with contact 117 and contact 117 into engagement with contact 118. When the coil 26 is energized by direct or alternating current it attracts armature 82 and pulls rod 84 to open engagement with contact 86 and close with contacts 90 and 89. Also contacts 86 and 87 will close by reason of the spring action of contact 86.

When it is desired to use the device the switch button 19 shown in Figs. 15, 16 and 17 is depressed so as to close the contact 20. When this is done 70 the resilient action of contact 120 will cause contact 120 to engage contact 102. This connects the motor 21 to a source of alternating current and causes the motor to immediately start and rotate the shaft 22 (Figs. 1 and 2) in the proper 75 direction to move an arm 23 (Figs. 2 and 12) into

engagement with a switch 24 (Fig. 12) so as to move it to the "on" position. At this time a condenser 25 (Fig. 17) provides a shunt path around a high resistance speaker field 26 for the alternating current, but as soon as the direct current from the rectifier 25' is established in the receiver it acts as a filter condenser. It will also be noted that the magnet 27 (Fig. 6) and the remote speaker field 26 are energized in series so that the respective armatures 28, 29 and 82 are attracted. 10 The attraction of armature 29 swings the bar 30 (Figs. 1, 2 and 18) which is pivotally mounted at 31 and 32 and as this bar is rigidly secured to an arm 33 said arm will be swung to the left, as shown in Fig. 2, until the resilient pawl 34 is 15 moved sufficiently to engage the next tooth on the ratchet wheel 35 (Fig. 2). The bar 30, the arm 33 and the bar 36 are preferably made in one piece. As arm 33 is rigidly secured to the block 36 as well as to the pawl 34, this block will be moved to 20 the left, as shown in Fig. 2, so as to pull the rod 37 which is preferably made of insulating material. This rod preferably extends loosely through the contact springs 38, 39, 40 and 41 and is provided with abutments 38', 39' and 40', which 25 simultaneously engage the respective springs and pull them to the left, as shown in Figs. 2 and 20. It will be understood, therefore, that when the arm 33 swings to the right, contacts springs 38 and 41 will be separated. Immediately before the 30 rod 37 functions, switch 24 will open and break the motor circuit.

In tracing the circuit when button 19 is depressed and starting with contact 20, alternating current will flow through wire 141, 140, switch 35 blade 139, contact 138, wire 137, wire 136, winding 135 of motor 21, wire 134, resistance 133, to wire 124 and then over wire 123, post 132, switch blade 131, wire 129, wire 127, winding 26 and condenser 25, wire 126, through spring 86, contact 88, wire 125 back to button 19. Alternating current flowing in the path just described will operate motor 21 and rotate shaft 22 and move shaft 22 to the left, as shown in Fig. 1, until the gear 72 meshes with gear 71. Power is transmitted from gear 72 45 through the miter gear 69, pinion 68 (Fig. 2), gear 67 and shaft 42' to shaft 42 for rotating pinion 46 which is in mesh with the bevel gear 48. This gear (48) is secured to pinion 50, which is continually in mesh with gear 51 secured to shaft 52 50 carrying arm 23 which is swung for moving the switch 24 to the "on" position. This turns on the direct current. As soon as the direct current has energized winding 26, armature 82 will be moved over to the left, as shown in Fig. 17, and will move 55 spring 85 into engagement with contact 90 and contact 90 into engagement with contact 89. This will open the circuit at contact 88 but direct current will continue to flow by passing through wire 127' to spring arm 90, spring arm 85, wire 125, 60 back to button 19. When armature 82 is attracted by magnet 26, current will flow from the rectifier 25' to the ground, through the ground to switch arm 139', wire 156, switch post 130, wire 129, wire 128, wire 127, winding 26, wire 126, spring arm 86, 65 contact 87, wire 153', switch 142, to wire 142', wire 146, wire 147, back to rectifier 25'. Current flowing in the circuit just described maintains the winding of the speaker 26 energized for operating the same. If the button 19 is held down after 70 switch 24 has been moved to the "on" position, direct current will begin to flow. If the button 19 is held down as just described, direct current will flow through a circuit including the winding of magnet 27 and winding 26 and will cause the 75

rod 37 to move to the left, as shown in Figs. 2 and 17, and will open the circuit of motor 21 by opening contacts 38'' and pull armature 28 to the left, as shown in Fig. 17, to secure certain results hereinafter described. When button 19 is held down as just described, current will flow from the rectifier 25'. Tracing the circuit, current will flow from contact 20, through wire 141, as indicated by arrows 141', wire 140, switch blade 139, wire 154', resistance 101, wire 144, winding of magnet 27, wire 155, wire 146 back to rectifier and from the opposite side of the rectifier 25' to ground and through ground to switch blade 139', wire 156, post 130, wire 129, wire 128, wire 127, winding 26, wire 126, contact spring 86, contact 88, wire 125 back to button 19.

If the station to which the device has been tuned is desired the button is completely released. However, if a different station is desired the button 19 is released sufficiently to break the circuit at contact 20, but not sufficiently to break the contact at 102. The button 19 is then pushed down for again closing the circuit at contact 20. This may be done once or as many times as necessary to bring in the desired station, one push being to advance the selector (ratchet wheel 35) one step. If the third station from the first were desired, three pushes on button 19 would be given and after the third push the button would be completely released and then the circuit including the contact 102 would be opened. When the button 19 is depressed the circuits through contact 102 and 20 are both closed so that direct current is supplied to the winding of magnet 27. When button 19 is raised slightly the circuit through contact 20 is opened but current will continue to pass to magnet 27 through contact 102 and the respective resistances 104 and 105 which will supply a weak current to magnet 27 but sufficiently strong to hold armature 28 moved to the left, as shown in Fig. 17. This will maintain contacts 106 and 107 and also contacts 106' and 107' open, while contacts 117' are maintained closed. This will prevent rotation of the motor 21.

When the button is completely released, the circuits through contacts 20 and 102 are both opened. This deenergizes the magnet 27 and releases the armature 28 whereupon contacts 106 and 107 and also contacts 106' and 107' will close and contacts 117' will open. If, for instance, the cam 17 shown in Fig. 7 was contacting with spring arm 14, current would flow from rectifier 25' through wire 147, wire 146, wire 155, winding of magnet 27, contacts 106 and 107, winding of magnet 27, contacts 106 and 107, winding of magnet 113, and winding of magnet of 108, to contact 110, through brush 97, brush 74, cam 17, to ground and through the ground back to rectifier 25'. Current flowing in this circuit opens contacts 106' and 107' and closes 106' and 115' while magnet 113 holds armature 114 against movement by armature 28. As magnet 27 is energized armature 29 is pulled for rocking bar 30 for swinging pinion 46 into mesh with bevel gear 47.

Substantially simultaneously with the flow of current in the circuit just described alternating current will flow through the motor 21. This alternating current flows from the alternating current transformer through wire 150, spring 41, contacts 39'' (spring 41 having been released by bar 92 having moved), spring 39, wire 151, spring 94, contacts 106' and 115', spring arm 115, wire 152, wire 153, winding 135' of motor 21, wire 134, back to the transformer. This will cause the motor to rotate and in turn rotate pinion 46, gear wheel 47, and shaft 49 for actuating the friction pulley 58

for rotating the disk 59 (Figs. 2 and 12), which is coupled to the condenser 3, as shown in Figs. 2 and 17. As soon as motor 21 starts to rotate shaft 22 will move to the left, as shown in Fig. 1, until the end of arm 96 slips off the shaft, whereupon the resilient action of arm 96 will close contacts 96'. The motor will continue to operate until the cam 17 (Fig. 7) moves off brush 74, whereupon the circuit of the direct current to magnets 27, 108 and 113 will be opened. When the circuit of magnet 108 is opened the spring arm 94 will move for opening contacts 106' and 115' and close contacts 106' and 107'. This will deprive magnet 27 of current and, consequently, the armature 29 will move away from the same and swing pinion 46 away from gear 47 and into mesh with gear wheel 48. When arm 96 slips off the shaft 22, contacts 96' are closed and as the armature 29 has already allowed the arm 33 and associated parts to move to the right, as shown in Figs. 2 and 17, the spring arm 40 is released and moves also to the right, as shown in Fig. 17, for closing contact 93' whereupon direct current will be supplied to the magnet 27. This will cause the armature 29 to be attracted for swinging arm 33 to open contacts 93'. This will deprive magnet 27 of current and armature 29, arm 33, panel 34 and associated parts will swing to the right (Fig. 17). This will again close the contacts 93'. This action is continued until the ratchet wheel 35 has reached a normal position, which is the position shown in Fig. 17 or a position 180° therefrom. While the step-by-step motion of the ratchet 35 and associated parts is taking place, a weak current flows through magnet 27 for attracting armature 28 for holding the contacts 106' and 107' open in order to prevent the rotation of motor 21 at this time. At the same time contacts 106 and 107 are maintained open to prevent energizing magnet 113.

When button 116 is depressed current will flow in a certain path including motor 21. Starting with button 116, current will pass through contact 119, resistance 105, wire 141, wire 140, switch blade 139, wire 154', resistance 101, wire 144, winding of magnet 27, wire 155, wire 146, wire 147 to rectifier 25', to the ground and through the ground to switch blade 139', wire 156, wire 129, wire 128, contact 90, contact 88 and wire 125, back to contact 119. Current flowing in this circuit will maintain magnet 27 energized so that it will continue to attract armature 28 but armature 29 will not be attracted by reason of the tension of the spring 40 associated with block 37.

When button 103 is depressed current will flow through a circuit including the winding of magnet 27. Starting with contact 102, current will flow through the resistances 104 and 105, wire 141, wire 140, switch blade 139, wire 154', resistance 101, wire 144, winding of magnet 27, wire 155, wire 146, wire 147, rectifier 25' to the ground, and through the ground to switch blade 139', wire 156, post 130, wire 129, wire 128, contact 90, contact 88 and wire 125, back to button 103 and contact 102. Button 103 and button 116 are used to actuate the volume control. From the above traced circuit it will be seen that when button 103 is depressed there will be an increase in volume. It will be noted that when the button 103 is depressed both the resistances 104 and 105 are in circuit and the armature 28 is attracted only sufficient to close contacts 118'. However, when button 116 is depressed resistance 105 only is included and the armature 28 is attracted to the fully operated position and contact 117' is closed. The contacts 117' and 118' control the direction of rotation of

the motor and, consequently, of the volume control. It will also be observed that the receiver is switched off by rotating the volume control in the decreased direction until the switch arm 23 snaps the switch 24 to the "off" position.

Starting with button 103 the circuit for energizing the magnet 27 to cause it to attract armature 28 and cause contacts 118' to be closed, is through wire 125, contact springs 85 and 90, wire 127', wire 128, wire 129, wire 156, switch blade 139', ground, direct current rectifier 25', wire 147, wire 146, wire 155, winding of magnet 27, wire 144, resistance 101, wire 154', switch blade 139, wire 140, wire 141, resistance 105, resistance 104, to contact 102 which is closed with spring 120. The circuit through contacts 118' is spring 117, spring 38, contact 38", spring 41, wire 150, secondary winding of alternating current transformer, wire 134, winding 135 of motor 21, wire 136, spring 95, and back to contacts 118'. These circuits rotate the motor for increasing the volume.

Starting with button 116 the circuit for energizing the magnet 27 to cause it to attract armature 28 and cause contacts 117' to be closed, is through wire 125, contact springs 85 and 90, wire 127', wire 128, wire 129, wire 156, switch blade 139', ground, direct current rectifier 25', wire 147, wire 146, wire 155, winding of magnet 27, wire 144, resistance 101, wire 154', switch blade 139, wire 140, wire 141, resistance 105, wire 119 and back to button 116. The circuit through contacts 117' is spring 117, spring 38, contact 38", spring 41, wire 158, secondary of alternating current transformer, wire 134, winding 135' of motor 21, wire 153, spring 118, and back to contacts 117'. These circuits rotate the motor for decreasing the volume.

The switches 20' and 119' have the same function as the buttons 103 and 116, respectively, when controlling the volume and the resistances 104' and 105' have the same function as the resistances 104 and 105, respectively.

In this specification it will be understood that when the term "gear" or "gear wheel" is used it includes toothed gears (beveled or spur) and also friction gears.

I claim:

1. In a remote control for radio receiving sets having an alternating current rectifier, a motor, a hand actuated switch for turning on alternating current to said motor, means actuated by said motor for simultaneously opening the circuit of the alternating current to the motor and hand actuated switch and thereby stopping the motor, said means also turning alternating current on said rectifier and at the same time connecting said hand actuated switch with the direct current circuit of the remote control for controlling the operation of the remote control.

2. In a remote control for radio receiving sets having a tuning condenser, means for moving the condenser for tuning including a rotatable shaft coupled to said condenser and electrically actuated means for rotating said shaft, a plurality of aligned cams freely rotatable on said shaft, a plurality of friction spiders secured to said shaft, the spiders being arranged so that one spider will be positioned between and act on each two cams and cause the cams to normally rotate with the spiders, a projecting member carried by each of said cams, a pivotally mounted locking arm for each of said cams, each of said locking arms having a notch for receiving a projection from a cam when the respective arms are moved into functioning position, a finger projecting

from one end of each of said arms, a movable selector having a notch for each of said fingers, and means for swinging said arms so as to cause the respective projecting members on the cams to enter the respective notches in said arms and the fingers to enter the notches in said selector, said notches in the selector being positioned so that only one finger at a time can enter a notch in the selector, whereby when any arm is interlocked with a projection from a cam it is held in a locked position.

3. In a remote control for a radio receiving set, a dynamic speaker having a voice coil and a field coil, an armature positioned to be attracted by the magnetism from said field coil, a hand actuated switch for momentarily closing a circuit including a source of direct current and said field coil, means actuated by said armature for closing and maintaining closed a circuit including a source of direct current and said field coil, said armature also closing and maintaining closed a circuit including said voice coil and the output of said receiving set.

4. In a remote radio control containing a first and a second switch, a motor and a tuning means, a magnetic gear shift structure consisting of a gear, a transmission shaft actuated by said motor and a pinion actuated by said transmission shaft and disposed adjacent said gear, a pivotal arm to move said pinion laterally so as to cause the pinion to mesh with said gear and thereby couple said motor and tuning means, and a pawl secured to said arm and disposed to engage the teeth of a ratchet wheel associated with the rotor of the second switch so as to cause step-by-step rotation of said second switch rotor on movement of said gear shift structure.

5. In a remote control containing a first and a second switch, a motor, tuning means and a volume control, a magnetic gear shift structure consisting of a pair of parallel gears, a transmission shaft actuated by said motor and a pinion actuated by said transmission shaft and disposed between said parallel gears, a pivotal arm positioned to move said pinion laterally so as to cause the pinion to engage one of the gears for coupling the motor and volume control and to engage the other gear for coupling the motor and tuning means, and a pawl secured to said arm and disposed to engage the teeth of a ratchet wheel associated with the rotor of the second switch so as to cause a step-by-step rotation of said second switch rotor on the movement of said gear shift structure.

6. In a remote control for a radio receiving set, a plurality of cams, each cam having part of its surface acting as a contact member, a circuit for each station to be selected and for each of said cams, a step-by-step switch for closing any of said circuits, means including a magnet for actuating said step-by-step switch, said switch having an individual contact for each of said circuits and a common contact for all of said circuits, each of said individual contacts including a spring arm positioned to engage the contact member or a cam when the contact member thereof is in position to close one of said circuits, means including a motor for actuating said cams, a circuit for said motor normally held open by said magnet whereby when said magnet stops functioning said motor circuit will close until said cams reach the setting for the selected station, a switch for connecting any of said individual contacts with said common contact, and means for actuating said switch.

7. In a remote control having a step-by-step switch for selective tuning, a tuning element, a motor, mechanical means having the dual purpose of coupling said motor and said tuning means and rotating the rotor of said step-by-step switch, an electromagnet having two armatures, one of which actuates said mechanical means, and a plurality of engaging contact springs for closing and shifting circuits of said motor to cause direct and reverse operations of the same in either direction.
8. In a remote control having a step-by-step switch for selective tuning, a tuning element, a volume control and a motor, an electromagnet having two armatures, one of which actuates a mechanical means having the triple purpose of coupling said motor and said tuning element, coupling said motor and said volume control, and rotating the rotor of said step-by-step switch, and the other engaging contact springs for closing and shifting circuits of said motor to cause direct and reverse operation of the same in either position of the first.
9. In a remote control having a tuning means, a step-by-step switch for selectively adjusting said tuning means, a volume control and a motor; an electromagnet having two armatures, one of which actuates a mechanism for rotating the rotor of said step-by-step switch to tune to a station, the other closing and shifting contacts for causing direct and reverse operation of said motor when coupled to said volume control for adjusting the volume; a winding and a circuit 10 for said winding, a circuit closer for closing said circuit directly to cause said magnet to actuate the first-mentioned armature, a resistance, a second circuit closer for closing said circuit through said resistance to cause said magnet to 15 actuate the second mentioned armature without moving the first-mentioned armature, a second resistance, and a third circuit closer for closing said circuit through said second resistance to cause said magnet to partially actuate the second 20 mentioned armature without moving the first.

DONALD C. FIERCE.
